UNITED STATES PATENT OFFICE.

JARED MARIS, OF COLUMBUS, OHIO.

DESIGN FOR A WHEEL-HUB.

SPECIFICATION forming part of Design No. 17,719, dated September 13, 1887.

Application filed June 18, 1887. Serial No. 241,802. Term of patent 14 years.

To all whom it may concern:

Be it known that I, JARED MARIS, a citizen of the United States, residing at Columbus, in the county of Franklin and State of Ohio, 5 have invented and produced a new and original Design for Wheel-Hubs, of which the following is a specification, reference being had to the accompanying drawings, forming part thereof.

10 My invention relates to a design for the ornamentation of wheel-hubs; and it consists in the flat central portion of the hub having a series of openings therein and the reduced ends, the extreme edge of one of which is 15 rounded, as shown.

In the accompanying drawings, Figure 1 is a view in side elevation of a hub embodying my design, and Fig. 2 is a view in end elevation of same.

20 A represents a hub of any desired size, having an enlarged flat central portion, *a*, and

reduced ends *c*. The central portion, *a*, of the hub is provided with a series of openings or sockets, *b*, and the outer edge of the reduced inner end of the hub is rounded off in a graceful curve, as shown at B. This curve is in the arc of a circle, and the size thereof can be varied at pleasure. 25

Having fully described my invention, what I claim as new, and desire to secure by Letters 30 Patent, is—

In a design for a wheel-hub, the ornamentation of the same, consisting in the enlarged flat central portion, the openings or sockets in said flat portion, and the reduced ends, the inner end having a rounded or convex outer edge, as shown and described. 35

JARED MARIS.
